VEHICLE SIDE FRAME TRUSS

William L. Sheppard, Philadelphia, Pa., assignor
to Edward G. Budd Manufacturing Company,
Philadelphia, Pa., a corporation of Pennsylvania

Application November 26, 1937, Serial No. 176,468

5 Claims. (CL 105—399)

- The invention relates to rail car bodies or the like and particularly to the vertical side wall truss structures of such bodies adapted to carry a substantial portion of the loads.
- 5 In general, it is a main object of the invention to provide such a structure having a minimum weight consistent with the load it is designed to carry and to produce such a structure at a considerable saving in cost of manufacturing.
- 10 It is a further object to provide such a structure which will more efficiently take the loads, which will effect a saving in the number of parts entering into the structure, a saving in assembly operations, and which will permit a larger degree of 15 standardization of parts entering into the structure.

These objects are in large measure achieved by an arrangement of the diagonals of the truss structure such that they radiate from common 20 points intermediate the top and bottom of the truss.

Other and further objects and the manner in which they are attained will become clear from the following detailed description when read in 25 connection with the drawings forming a part thereof.

In the drawings:

Figure 1 is a fragmentary perspective view, parts being shown in section, of part of the 30 side wall of a rail car body structure having the invention embodied therein.

Figure 2 is a fragmentary side elevational view of a part of the side wall truss structure according to the invention, parts being broken away 35 to show the joint from which the diagonals radiate.

Figure 3 is a detailed sectional view on an enlarged scale through the joint, the section being taken approximately on the line 3—3 of Figure 2 looking in the direction of the arrows at the 40 end of the section line.

As shown in the drawings, the invention is applied to a light weight rail car construction in which the vertical side trusses are main load carrying elements of the structure. Such trusses usually comprise through-running bottom sills or chords 10 arranged substantially at the floor level of the body, through-running intermediate sills or chord members 11 arranged just below the window openings 12 and through-running top sills or chords 13 arranged just above the window openings 12. The vertical members of the trusses comprise relatively closely longitudinally spaced posts 14 and 15 rising between two adjacent window openings which openings are relatively 55

wide as compared to the spacing between the posts 14 and 15. This arrangement provides a series of pairs of posts 14 and 15, one pair arranged between each pair of adjacent window openings.

According to the invention, the truss is completed by sets of diagonals 16, 17 and 18 radiating from their connection with an intermediate portion of the post 15 to the top and bottom of the adjacent closely spaced post 14 and to the bottom of the post 14 on the other side of the window opening adjacent the post 15. To further interconnect the bottom chord 10 and the intermediate chord 11 and to stabilize the long diagonal 18, they may be interconnected by the vertical member 19 at an intermediate location between the widely spaced posts 14 and 15. The posts 15 from which the diagonals radiate or at which they are focused may be of lighter construction than posts 14. In the drawings these posts 15 are simple channels facing longitudinally while the posts 14 are laterally facing flanged channels.

According to the form of the invention shown, the bottom chord 10 is a built-up structure consisting of a through-running outer flanged channel 20, a through-running inner vertically deep plate 21, a through-running floor stringer of inwardly facing channel section 22 and a bottom angle 23 and a top downwardly facing channel 24. These parts are spot welded together in their overlapping regions to form a strong box-section sill structure. The top of this sill structure may be additionally reinforced by a through-running angle 25 spot welded through one of its arms to the top margin of the plate 21.

The intermediate sill 11 is also a built-up structure comprising the through-running outer flanged channel 26, the inner through-running plate 27, and the top and bottom channels 28 and 29 spacing the through members and spot welded thereto in their overlapping portions to form box-section sill structures.

The top chord member 13 in the final assembly also comprises a composite sill structure consisting of an outer inwardly facing through-running flanged channel 30, an inner through-running plate 31 and upwardly and downwardly facing flanged through-running channels 32 and 33 spacing the channel 30 and plate 31 and spot welded thereto throughout their length and to each other to form a very strong top chord structure.

The posts 15 are longitudinally facing channels passing through the box-section bottom sill 10 and the intermediate box-section sill 11 and hav-

ing side walls spot welded in the case of the bottom sill to the plate 21 and flanges of the channel 20, and in the case of the intermediate sill 11 to the plate 27 and to the flanges of the channel 26.

Similarly the posts 14 which are shown as outwardly facing flanged channels also pass through sills 10 and 11 and are secured through their flanges to the flanges of the channels 20 and 26 and through their bottom walls to the plates 21 and 27.

At the top, posts 14 and 15 telescope within the channel 33 of the top sill 13 and are spot welded to the side walls thereof.

15 To more securely tie the posts 14 and 15 into the longitudinal members 10, 11 and 13, gussets are provided and these gussets are to a considerable degree standardized so that the same gusset can be used in a number of different locations.

20 For example, the gussets 34 for securing the posts 15 to the bottom sill 10 and the posts 14 to the intermediate sill 11 are identical. So also the inner and outer gussets 35 and 36 for securing the top of the posts 14 to the top sill 13 may be identical except for a cut-out in the gusset 35 to receive a window. Also the outer and inner gussets 37 and 38 for securing the top of the post 15 to the top sill 13 are identical except for this cut-out. Likewise the generous outer and inner gussets 39 and 40 which join the intermediate sill 11, post 15 and the diagonals 16, 17 and 18 radiating therefrom are also identical in form.

35 As shown in Figures 2 and 3, these gussets have a substantial overlap with the side walls of the post 15, the flanges of the through-running longitudinal channel 26, the plate 27 and the ends of the channels 28 and 29 and are welded to these members by a generous number of spot welds to these overlaps. As shown in Figure 3, 40 the ends of the channels 28 and 29 overlapping the gussets are inwardly offset to an extent equal to the thickness of the metal of the gussets so as to provide a flat face for the securement of the through-running channel 26 and the through-running plate 27.

45 The diagonal 16 is stiffened by forming it of two channels secured back to back and is telescoped between the gussets 39 and 40 to which it is spot welded through the side walls of the channels forming it. At its opposite end the diagonal 16 is similarly telescoped between the gussets 35 and 36 and spot welded to them through the side walls of its channels. The diagonal 18 is similarly formed and similarly 50 joined to the gussets 39 and 40 at one end. At its opposite end it is telescoped between the plate 21 and an outer gusset 41 of generous proportions and is spot welded through the side walls of its channels to the plate and gusset. 55 This gusset also has a wide overlap with the post and with the bottom sill 10 and is connected thereto by spot welding through said overlap. The diagonal 17 is of lighter construction than the diagonals 16 and 18 being a simple channel telescoped at one end between the gussets 39 and 40 and spot welded thereto through its side walls and at the opposite end between the plate 21 and gusset 41 to which it is similarly secured through its side walls.

70 The vertical members 19 extending between the intermediate sill 11 and the bottom sill 10 are preferably formed in two parts, the adjacent ends of which telescope within the channels of the diagonal and are secured thereto by spot welding, their opposite ends extending respectively

between the outer and inner through-running members of the intermediate and bottom chords and being spot welded thereto.

By reference to Figure 2, it will be noted that the axes of the diagonals 16, 17 and 18 all pass through the mid-point of the joint between the post 15 and the longitudinal chord 11 so that the stresses are uniformly distributed. Also this arrangement of diagonals permits the joinder of the diagonals to the post 15 with the minimum number of welds and provides a structure which can most efficiently take the loads to which it is subject by reason of the fact that most of the loading on the diagonals is in tension. Since this is so, the structure can be correspondingly lightened. By this construction also the assembly of the parts is greatly facilitated and the fabrication of the parts themselves is simplified.

The arrangement of posts and diagonals and their connection to the longitudinal chords is such as to place the welds joining these posts in shear and to constitute the connections between these posts substantially of equal strength on opposite sides of the central vertical longitudinal plane of the truss.

Reference is made herein to copending application Serial No. 193,870, filed March 4, 1938, a division of application Serial No. 720,650, filed April 14, 1934, (now Patent No. 2,171,434), this copending application showing a side wall truss structure generally similar to the truss shown in this application and claiming common subject matter.

While I have herein described a specific form which the invention may take, it will be understood that changes and modifications may be made by those skilled in the art which still fall within the spirit and scope of the appended claims.

What I claim is:

1. A load carrying side frame truss for vehicle bodies comprising a bottom chord adjacent the floor level of the body, a top chord above the window openings of the body and an intermediate chord below the window openings, said chords comprising through running outside and inside elements, angular section posts arranged in pairs between the window openings and each pair of posts being closely spaced as compared with the width of the window openings, said posts passing between the outside and inside elements of the chords and secured thereto, said outside and inside elements of the chords being connected by bridging elements extending between them and secured thereto, and angular section diagonals focused at the joint between one of the posts of a pair and the intermediate chord and extending from said joint, respectively, one to the joint of the bottom of the other post of a pair with the bottom chord, another to the joint of the top of said other post with the top chord, and a third to the joint of the other post of an adjacent pair with the bottom chord, the diagonals being secured through opposed outside and inside gussets to the joints of the posts and chords substantially equally on the opposite sides thereof so that the compression or tension loads thereon are substantially equally distributed on the opposite sides of the vertical central plane of the truss.

2. A load carrying side frame truss for vehicle bodies comprising bottom, intermediate and top chords, said chords comprising through running outside and inside elements and bridging members joining said outside and inside elements, angular section posts interconnecting the chords

and passing between the outside and inside elements thereof and secured thereto, and angular section diagonals radiating from the joint of one of said posts with the intermediate chord, one to the joint between the bottom of an adjacent post and the bottom chord, another to the joint between the top of said adjacent post and the top chord and a third to the joint between the bottom of a third post and the bottom chord, said diagonals being secured through opposed outside and inside gussets to the joints of the posts and chords substantially equally on the opposite sides thereof so that the compression or tension loads thereon are substantially equally distributed on the opposite sides of the vertical central plane of the truss.

3. A load carrying vehicle body side frame truss comprising bottom, intermediate and top chords, said chords comprising through running outside and inside elements and bridging members joining said outside and inside elements, angular section posts interconnecting said chords and passing between the outside and inside elements thereof, said posts being alternately closely and widely spaced, and angular section diagonals radiating from the joint between one of said posts

with the intermediate chord, one to the joint between the bottom of a closely spaced post with the bottom chord, another to a joint between the top of said closely spaced post with the top chord and a third to the joint between the bottom of a widely spaced post and the bottom chord, said diagonals being secured through opposed outside and inside gussets to the joints of the posts and chords substantially equally on opposite sides thereof so that the compression or tension loads thereon are substantially equally distributed on the opposite sides of the vertical central plane of the truss.

4. A vehicle body side frame truss according to claim 3 in which a vertical strut joins the intermediate portion of the long diagonal to the bottom and intermediate chords.

5. A vehicle body side frame truss according to claim 2 in which the radiating diagonals are joined for equal distribution of the loads thereon to the posts and intermediate chords by inside and outside gussets common to the radiating diagonals and intervened between the posts and the inside and outside chord elements, respectively.
